[57] CLAIM

The ornamental design for a trash receptacle, as shown and described.

DESCRIPTION

FIG. 1 is a perspective view of a trash receptacle embodying our design;

FIG. 2 is a top plan view thereof;

FIG. 3 is a front elevational view thereof;

FIG. 4 is a side elevational view thereof, the opposite side being a mirror image thereof;

FIG. 5 is a rear elevational view thereof;

FIG. 6 is a bottom plan view thereof; and

FIG. 7 is an enlarged fragmentary view illustrating the textured surface of the body of the trash receptacle, said view being taken in area VII of FIG. 3.

The areas in all views represented by line shading show a contrasting surface.
